VALVES AND MANUAL ACTUATORS THEREFOR

Stoian Georgieff, Avellaneda, Argentina

Application June 9, 1953, Serial No. 360,565

2 Claims. (Cl. 251—289)

The present invention is related to faucets, cocks and such like in general and, more particularly, to improvements in this branch of closure means and it aims at providing faucets, cocks and such like which comprise at least one common valve element operatively connected with control elements allowing of an intermittent opening of the faucet with automatic closure, as well as the opening of the same for any length of time, in which case the closure is intentional, all of which shall be explained hereinafter.

For a better understanding of the object of the present invention, two preferred embodiments thereof have been illustrated, merely by way of example which by no means limits its scope, in the appended drawings, in which:

Figure 1 is a side elevation of a possible embodiment of the new faucet or cock, in which all the valve element control means are in the position corresponding to the closure of the faucet or cock.

Figure 2 is a side elevation of another possible embodiment of the improved faucet or cock, in which the control means are so arranged that the valve element, lifted off its seat, allows the liquid to flow through the passage of the faucet or cock.

Figure 3 is a longitudinal section through the improved faucet or cock as shown in Figure 2.

With reference now to the attached drawings, the faucet, cock or the like, comprises a tubular body 1 of any suitable shape, the passage 2 of which, open at both ends, is divided at an intermediate point of its length by a partition 3 into two adjoining portions *a* and *b* communicating through an opening 4 suitably provided in the body of the partition 3. This opening is provided at one of its ends with a valve seat 5 for cooperation with an axially displaceable closure element 6. The improvements introduced into the new faucet are characterized in that the said control elements include, for the closure of the faucet, at least one expansion coil spring 7 and, for the opening of the same, at least one axially displaceable element 8, one end of which, jutting out beyond the tubular body 1, is borne upon the free end portion of one of the arms 9*a* of the suitably arranged rocking element 9, the other arm 9*b* of which is operatively engaged with a rockingly sustained lever 10 having an arm 10*a* provided with an extension 11 pivoted at one of its ends.

The expansion coil spring 7 is freely wound around the perimeter of a cylindrical projection 12 fixed at one of its ends to the body of a removable lid 13 closing the open free end of a tubular branch 14 integral with the body 1 of the faucet or cock, the said cylindrical projection 12 being provided with an axial cavity 15 in which is freely housed a movable pin 16 provided, in the usual manner, intermediate its ends with the plate or closure element 6 bearing a washer (not shown) made of any suitable material and secured to the plate in any suitable manner. One end of the said spring 7 bears against the inner bottom of the lid 13 and the other one

2

against the adjacent face of the plate controlling the closure means fixed on the bearer pin 16.

The axially displaceable element 8 is constituted by a plunger axially displaceable within the passage 17 of the tubular branch 18 integral with and jutting out beyond the body of the faucet 1, the outer end of the said branch 18 being provided with a ring-shaped nut 19 and packing 20, both of which constitute an adjustable stuffing-box.

10 The axially displaceable plunger 8, suitably housed within the passage 17, is axially provided at its inner end with a relatively long projection 21 having an essentially reduced diameter, the free end portion of which passes through the valve opening 4 and bears concentrically against the adjacent face of the closure means 6, and, at its outer end, with another, relatively short projection 22 having an essentially reduced diameter, suitably and freely engaging a nut 23 provided in the body of the arm 9*a* of the rocking element 9.

20 The said rocking element 9 is suitably pivoted at 24 on the bearing means 25 fixed at one end to the body 1 of the faucet, whilst the second arm 9*b* of the said rocking element is provided with another notch or groove 26 for engaging the free end of the extension 11 pivoted 25 at its other end on the adjacent free end of the arm 10*a* of the control lever 10 rockingly pivoted at 27 on the bearing means 28 fixed to the body 1 of the faucet.

The free end of the arm 9*b* of the rocking element 9 is provided at a point adjoining the notch or groove 26 with a tooth 29 constituting a limiting stop for the control arm 10 with its extension 11 for the purpose of fixing the position of these control means when the faucet is to remain open for any length of time.

35 The rocking element 9 may bear at any suitable point of its body and virtually in an apparently perpendicular form with respect to its length, a projection 30 provided with a push plate 31 at its free end portion, the said projection 30 and its push plate 31 constituting a second control means for intentionally opening the faucet by 40 submitting the said push plate 31 to pressure and for permitting automatically closing the same by the interruption of the said pressure.

45 When it is desired to open the faucet and secure it in this position, the control lever 10 is pivoted from its position I to its position II. This change of position increases the lineal distance between the joint 27 and the free end of the extension 11, which causes the rocking element 9 to pivot at 24 until the inclination of the extension 11 is inverted at the joint 32 which is so limited by the abutment of the said extension 11 against the tooth 29 as to 50 exclude any possibility of an undue return movement of the control lever 10 and, at the same time, to secure the said lever 10 in position II. When the rocking element is pivoted in the above manner, it causes the element 8 to be axially displaced, the projection 21 of the latter pushing the closure element 6 off the seat 5 of the opening 4 and submitting the spring 7 to tension or compression. The clearing of the passage 4 allows of the flow of the liquid from the inlet through the portion *a* 55 of the passage 2 to the portion *b* of the said passage 2, whence it is eventually discharged through the open outlet end of the tubular body 1. When it is desired to interrupt the flow of liquid, it is only necessary to operate the control lever 10 pivoting it somewhat from its position II towards its position I so as to pass the point of inversion of the articulation of the elements 10 and 11 and to set free the compressed spring, whereby its 60 expansion causes the automatic closure of the passage 2 due to the closure of the opening 4 by means of the element 6.

70 Should it be desired to open the faucet only for a moment and without securing the open position in the

above specified manner, the plate 31 of the projection 30 is pressed down causing the rocking element 9 to pivot in the above specified manner, whereby the element 8 is displaced and the closure means 6 lifted off the seat 5 of the opening 4 allowing of the discharge of the liquid whilst the said plate 31 is submitted to pressure, and as soon as it is interrupted, the spring 7 expands and causes the closure of the opening 4.

The extraordinary advantages offered by the improved faucet or cock may be fully appreciated from the foregoing specification. It allows of a better operation of the same in two different forms, for which purpose two control means are provided to be used alternatively as the case may be. Furthermore, it should be pointed out, that the manufacture of this improved faucet offers no difficulties whatever and its constituent parts are readily available. Another extremely important feature of the improved faucet consists in that its parts are not subject to twisting thereby allowing of a wider range of materials for its manufacture.

It is to be understood that certain changes of detail and construction may be introduced in the herein disclosed embodiments of the present invention without departing from its real scope as defined in the appended claims.

What I claim is:

1. A faucet comprising a hollow body having an inlet passage, an outlet passage, and an inner partition separating said inlet and outlet passages, said partition having an opening therein through which said inlet and outlet passages are adapted to be placed in communication, a valve member for closing said opening, a rod guided for axial movement in said hollow body, said rod serving to carry said valve member, one end of said rod projecting outwardly of said hollow body, a rocker member pivotally mounted intermediate of its ends to said hollow body, one end of said rocker member engaging said rod whereby said valve member may be moved away from said opening in said partition upon rocking movement of said rocker member, an operating lever pivotally mounted intermediate of its ends to said hollow body at a point remote from and above the pivotal connection of said rocker member with said hollow body, a connecting link pivotally mounted at one end to said lever and at the other end engaging the other end of said rocker member whereby the latter may be rocked as the distance between the said other end of said connecting link and the pivotal mounting of said lever is

varied upon pivotal movement of said lever, and said lever and connecting link when aligned serving to hold said valve member in an open position through interaction with said rocker member and said rod.

2. A faucet comprising a hollow body having a rear portion constituting the inlet passage connectable to piping, a front portion constituting the outlet passage, and an inner partition dividing the cavity of the hollow body and separating said inlet and outlet passages, said partition having an opening therein through which said inlet and outlet passages are adapted to be placed in communication, a valve member for closing said opening, said body having an opening therein communicating with said inlet passage, a lid closing said last named opening, a cylindrical projection extending from the inner face of said lid and having an axial guide cavity therein for receiving the upper portion of a rod carrying said valve member, the lower portion of said rod projecting outwardly of said hollow body, a rocker member pivotally mounted intermediate of its ends to said hollow body, one end of said rocker member engaging said rod whereby said valve member may be moved away from said opening in said partition upon rocking movement of said rocker member, an operating lever pivotally mounted intermediate of its ends to said hollow body at a point remote from and above the pivotal connection of said rocker member with said hollow body, a connecting link pivotally mounted at one end to one end of said lever and at the other end engaging said other end of said rocker member whereby the latter may be rocked upon pivotal movement of said lever, the other end of said lever serving as a first operating handle, and an arm member extending from said rocker member adjacent the pivotal mounting thereof and serving as a second operating handle.
